US00D873467S

(12) **United States Design Patent** (10) Patent No.: **US D873,467 S**
(45) Date of Patent: ** *Jan. 21, 2020

(54) **LIGHT FIXTURE**(71) Applicant: **HGCI, Inc.**, Las Vegas, NV (US)(72) Inventor: **Christopher Reynolds**, Vancouver, WA (US)(73) Assignee: **HGCI, Inc.**, Las Vegas, NV (US)

(*) Notice: This patent is subject to a terminal disclaimer.

(**) Term: **15 Years**(21) Appl. No.: **29/623,160**(22) Filed: **Oct. 23, 2017****Related U.S. Application Data**

(63) Continuation of application No. 29/576,115, filed on Aug. 31, 2016, now Pat. No. Des. 804,078.
